UNITED STATES PATENT OFFICE

2,625,177

PILOT OPERATED QUICK OPENING
CONTROL VALVE

Joseph F. Ziskal, Cicero, Ill., assignor to International Harvester Company, a corporation of New Jersey

Application November 19, 1947, Serial No. 786,988

2 Claims. (Cl. 137—668)

1

This invention has to do with a control for connecting the output of a constant delivery pump with a place for delivery of liquid at relatively low pressure upon termination of the connection of the output with a place for delivery of liquid at a relatively high pressure, the control employing a by-pass passage and a by-pass valve therein which is opened for providing communication between the pump output and the place for delivery at low pressure.

This invention constitutes an improvement over by-pass valve control mechanism disclosed in the copending application of Clarence A. Hubert and Joseph F. Ziskal, Serial No. 689,732, filed August 10, 1946, for Hydraulic Ram and Control. Therefor, now abandoned, and continuation filed June 18, 1952, Serial No. 294,394. Such improvement concerns an improved plunger of a fluid actuated control actuator of the apparatus for opening the by-pass valve, and it is the general object of this invention to provide an improved plunger structure wherein there is a spring which is energized by an initial advancement of a part of such structure for developing a force which is subsequently for effecting wider opening of the by-pass valve than would occur without the presence of the spring.

More specific objects of the invention include:

A by-pass valve operating plunger employing independently axially movable parts of which one is operable when axially advanced to unseat a seated member of the by-pass valve for opening such valve, and the other of such parts being advanceable under fluid pressure for compressing a spring during an initial advancement of such other part and thereby energizing the spring for enabling it to project the valve member farther from its seat subsequent to an initial unseating thereof while the spring reacts against said other part; and the provision of a new fluid actuated plunger having axially expandable and contractable parts together with a partially compressed spring therebetween urging said parts into an expanded condition and means for limiting the degree of expansion of said parts under the force of said spring.

These and other desirable objects inherent in and encompassed by the invention will become apparent from the ensuing specification and the drawings, wherein:

Fig. 1 is a partially diagrammatic view of a hydraulic system employing a constant delivery pump and by-pass valve and illustrating a by-pass valve operating plunger constituting a preferred embodiment of the invention for unseating a seatable member of such valve.

2

Fig. 2 is a fragmentary sectional view taken on a plane which extends axially through a multiple-spool valve of Fig. 1, and illustrating such valve in an operating position in contrast to the neutral position shown in Fig. 1.

With continued reference to the drawings, the invention is there illustrated in conjunction with a hydraulic circuit which is adapted to selectively deliver fluid under high pressure conditions from the output side of a constant delivery pump 11 to either end of a two-way operable hydraulic ram 12 or to divert the fluid from the pump at relatively low pressure to a reservoir (not shown) upon the ram piston 13 reaching a predetermined position in the ram cylinder under force of the high pressure fluid. The significant structural differences in the hydraulic system herein disclosed and the disclosure in said copending application, Serial No. 689,732, is confined to a plunger structure 14 which is advanceable in a cylinder 15 to the position illustrated in Fig. 1 for unseating a by-pass valve ball member 16 from a seat 17 of a by-pass valve 18. The corresponding plunger structure disclosed in the copending application is a solid or rigid element in contrast to the fabricated structure 14 which employs a partially compressed spring 19 held captive between telescopically associated parts 21 and 22. The part 21 is a cup-shaped member having a central bearing opening 23 in its bottom or left end. A cylindrical side wall of the part 21 slides as a piston in the cylinder 15. The part 22 comprises a stem 24 having a pilot flange 25 projecting radially from a central portion thereof for sliding axially upon the cylindrical inner periphery of the part 21.

The left end of the stem 24 projects through and is piloted in the bearing opening 23, and a retaining pin 26 extending diametrically through the left end portion of the stem 24 is abuttable against the left end of the part 21 for holding the partially compressed spring 19 captive between the flange 25 and the bottom of the cup-like part 21. A breather opening 27 in the flange 25 facilitates expansion and contraction of the parts 21 and 22. An explanation of the mode of operation of this plunger structure appears hereinafter in conjunction with the operation of the entire system of which it forms an element operating in sequence with other elements.

A spool valve structure 31 comprises a multiple-ported cylinder 32 in which a multiple-spool valve element 33 is axially slidable. An annular inlet chamber 34 within the cylinder 32 between

lands 35 and 36 of the element 33 is connected with the output side of the pump 11 through diagrammatically illustrated conduits 29 and 30 and a cylinder port 38. When the spool valve element 33 is in the neutral position illustrated in Fig. 1, the fluid in the chamber 34 can escape through neither the admission valves 35-39 nor 36-41. Consequently, fluid of the constant delivery pump 11 is discharged through the conduit 29 into a by-pass passage 42 of the apparatus. From the by-pass passage 42 some of the fluid is conducted through a transfer passage 43 which is caused to be of limited flow capacity by a plug 44 having a small calibrated bore 45 through which the fluid can flow. This transfer conduit or passage 43 communicates between the by-pass passage 42 and a control chamber 46 which is blocked off at one end or side by the plunger structure 14.

Also communicating with the control chamber 46, through a portion of the passage 43, is a control passage 47 which has branches 47^a and 47^b leading respectively to ports 48 and 49 of control valves 48-51-52 and 49-53-54. With the spool valve element 33 in the neutral position of Fig. 1, each of the control valves 48-51-52 and 49-53-54 is closed, wherefore the fluid entering the transfer passage 43 from the by-pass passage 42 is effective for creating fluid pressure in the control chamber 46 equal to the pressure in the up-stream portion of the by-pass passage 42, that is, that portion of the by-pass passage 42 which is on the up-stream side of the by-pass valve seat 17. Since the plunger structure 14 presents an area to the control chamber 46 in excess of the area circumscribed by the by-pass valve seat 17, a unit pressure of fluid in the chamber 46 equal to and in fact somewhat less than the unit pressure of fluid in the up-stream portion of the by-pass passage 42 will be effective for advancing the plunger structure 14 to the right to unseat the by-pass valve member 16 and maintain the same unseated against pressure of fluid in said up-stream passage portion in the manner illustrated in Fig. 1.

Prior to the unseating of the valve member 16, the entire plunger structure 14 will be somewhat to the left of the position illustrated in Fig. 1. The spool valve element 33 will then be either to the left or the right of the neutral position of Fig. 1. Assuming the valve element 33 to have been moved to the left of neutral as illustrated in Fig. 2 by a manual force applied to the lower end of a lever 55 by a pivotally connected control rod 56 while the upper end of the lever 55 is constrained against movement by a pivotal connection 57 with a piston rod 58 of the hydraulic ram 12, the control valve 48-51-52 will have been opened. This permits escape of fluid from the transfer passage 43 to the reservoir through a conduit 59. Such escape of fluid through this control valve causes a diminution of the fluid pressure in the control chamber 46 because the escape of such fluid is at a substantial rate compared to the replacement capacity of the small bore 45 in the plug 44. With this diminished pressure of the fluid in the control chamber 46, the pressure of fluid in the up-stream portion of the by-pass passage 42 together with the force of a compression spring 61, will prevail over the force of fluid pressure upon the left end of the plunger structure 14 and cause seating of the by-pass valve member 16.

With delivery or output of the constant delivery pump thus precluded from escaping past the by-pass valve 18, and only an inconsequential

quantity of the output capable of escaping through the small bore 45 in the fluid transfer passage 43, essentially the entire output of the pump is delivered through the conduit 30 and the port 38 into the valve chamber 34. However, since the spool element 33 is then in a position wherein the delivery valve 35-39 is open, the fluid introduced into the chamber 34 is discharged through the port 39 and a conduit 62 into the left end of the hydraulic ram 12. Thus the ram piston 13 is moved to the right, causing discharge of fluid through a conduit 63 and the port 41 of the then opened control valve 36-41, thence through an axial bore 64 in the valve spool, thence through the port 52 and the conduit 59 to the reservoir.

Movement of the ram piston 13 to the right under the circumstances just explained, causes movement of the upper end of the lever 55 to the right while the lower end of said lever is held against movement by the "set" control rod 56. This pivoting of the control lever 55 causes retraction of the valve stem 33 toward neutral, and concurrently with the piston 13 having moved to the right a distance correlated with the amount of manual movement initially imparted to the lower end of the control lever 55 for displacing the spool element from the neutral, said valve spool element will be returned to neutral. The delivery valve 35-39 will then be closed as will the delivery valve 36-41, hydraulically locking the piston 13 against further movement. The control valve 48-51-52 will also be closed, precluding further escape of the fluid entering the transfer passage 43, wherefore pressure quickly builds up in the control chamber 46. As the pressure is thus caused to increase in the control chamber 46, an increasing force is applied to the left end of the control plunger part 21, causing this part to move to the right, the by-pass valve member 16 then being seated at 17. Concurrently, the pressure of fluid in the up-stream portion of the by-pass passage 42 together with the force exerted by the spring 61 will be urging the valve member 16 seated and will prevail over the initial force transmitted from the fluid of increasing pressure in the chamber 46 against the plunger part 21 through the compressible spring 19 and the part 22 in an up-stream direction against the valve member 16. During this ephemeral time that the pressure in the up-stream passage portion prevails over the pressure in the control chamber 46, in maintaining the valve member 16 seated, the part 22 will be constrained by the seated valve member against advancement to the right while the part 21, which is being advanced by the increasing pressure of fluid in the chamber 46, causes the spring 19 to be compressed and energized.

Eventually the force transmitted to the valve member 16 through the compressed spring 19 and the part 22 will reach a magnitude exceeding that of the combined force of the fluid in the up-stream passage portion and of the spring 61 and cause unseating of the member. The initial unseating of the valve member 16 will allow escape of fluid therewith over the seat 17 and outwardly of a down-stream portion of the passage 42 and a conduit 65 to the reservoir. Such escape of fluid through the "cracked" (initially opened) by-pass valve diminishes the pressure in the up-stream portion of the passage 42, enabling the compressed spring 19 to instantly expand to its captive limit determined by abut-

ment of the stop pin 26 with the left end of the part 21. While so expanding, the spring 19 reacts against the part 21, which is maintained in position by the non-compressible liquid, and projects the part 22 and the valve member 16 sufficiently far to open the by-pass valve widely. Such wide opening of the by-pass valve 18 enables the fluid from the constant delivery pump to escape through the by-pass passage at lower pressure than if such valve were less widely opened. Diminished by-pass pressure involves less heating of the by-pass liquid and also requires less energy for driving the constant delivery pump.

The fabricated plunger 14 employing the spring 19 is capable of causing wider opening of the by-pass valve than a one piece or rigid plunger in identical systems where such plungers are installed. If a rigid plunger were substituted for the plunger structure 14, the increase of pressure of the liquid in the control chamber 46 would eventually reach a magnitude for bodily advancing the entire rigid plunger for initially unseating the by-pass valve member 16 at the same chamber pressure required for causing the plunger structure 14 to initially unseat such valve member. However, because of the non-compressible character of the liquid in the control chamber and because of the rigid character of the previously employed plunger, this initial "cracking" of the by-pass valve and the diminution of pressure in the up-stream portion of the by-pass passage would not be followed by an accelerated projection of the by-pass valve member into a wider opened position. The rigid plunger and the valve member would be more gradually advanced to the right by the increased volume of non-compressible liquid accumulating in the control chamber until a balanced status is reached wherein the combined force of the fluid in the up-stream portion of the by-pass passage and the spring 61 acting in a down-stream direction upon the by-pass valve member equals the force exerted in an up-stream direction upon said valve member by liquid in the control chamber 46. This balanced status is eventually reached because diminution of pressure in the up-stream portion of the by-pass passage directly controls the pressure in the control chamber 46 through the transfer passage 43. But when the fabricated plunger structure herein disclosed is employed, a greater quantity of fluid is introduced into the control chamber 46 prior to "cracking" the by-pass valve because of the permissible advance of the plunger part 21 by the compressible spring 19. After "cracking" of the by-pass valve, the energy in the compressed spring projects the valve member 16 off its seat a distance which is greater than otherwise in an amount proportional to the additional volume of fluid in the control chamber 46. This results in all of the displaceable parts, the structure 14 and the member 16 being displaced to the right a greater distance than if the spring 19 were not present, and the consequent lower pressure in the up-stream portion of the discharge passage 42 does not subsequently retract the valve member 16 and the plunger structure 14 to a position that would be occupied thereby if a plunger not employing the spring 19 were used. With the valve member 16 initially projected farther from the seat 17 by the spring 19 a corresponding initial lower pressure will prevail in the up-stream portion of passage 42, causing

lower pressures to obtain in both this passage portion and in the control chamber at which a balanced position is established for said valve member. Substitution of a plunger structure like 14 for a rigid plunger in a cylinder 15 of apparatus like that illustrated in the present drawings has caused reduction of by-pass pressure from approximately 45 lbs. per square inch to approximately 10 lbs. per square inch.

Movement of the valve spool element 33 from the neutral position of Fig. 1 in the opposite direction to that illustrated in Fig. 2 will commence a sequence of operations similar to that described above but causing the fluid from the valve chamber 34 to be discharged through the port 41 and the conduit 63 into the right end of the ram cylinder 12 and discharge of fluid from the left end of said cylinder through the conduit 62, port 39, valve spool passage 64, and the port 54 to the reservoir. This opposite movement of the valve spool element will also cause the control valve 49-53-54 to establish communication between the control chamber 46 and the reservoir with the effect of the control valve 48-51-52 as explained above. The principal difference in the operation of the apparatus is to cause movement of the ram piston 13 in the opposite direction, and upon the spool valve element 33 being returned to neutral when the movement of the ram piston is completed, the closing of the control valve 49-53-54 will terminate escape of fluid delivered into the transfer passage 43 and cause the building up of pressure in the control chamber 46 for again opening the by-pass valve 18.

A pressure relief valve 71 is normally inoperative. This relief valve comprises a plunger 72 urged to the right by a spring 73 which normally maintains a perforated stem 74 in the position illustrated in Fig. 1, but responsive to abnormal pressure in the by-pass passage 42, this plunger and the stem 74 will be forced to the left to carry holes 75 of the stem 74 into communication with a passage 76 which is communicative with the reservoir through the conduit 65.

Having thus described a single preferred form of the invention with the view of clearly and concisely illustrating the same, I claim:

1. In apparatus for controlling the flow of liquid through a by-pass passage; a by-pass valve disposed in said passage between up-stream and down-stream portions thereof and including a valve seat circumscribing said passage, and a valve member seatable in a down-stream direction upon said seat for closing such seat; means for unseating said valve member comprising a control cylinder, a plunger structure blocking off a control chamber in the cylinder and comprising parts which are individually advanceable axially of the cylinder by the force of liquid under pressure in said chamber, and captive spring means between and distortable by said parts for exerting a valve-opening force through one of said parts against the valve member in an up-stream direction to displace the same from said seat pursuant to advancement of the other of such parts by the force of liquid under pressure in the chamber; a liquid transfer passage communicating between said chamber and up-stream passage portion, said plunger structure having a transverse area subjected to the liquid in the chamber exceeding the area embraced by the valve seat wherefore an advancing force 35 exerted on the plunger structure by liquid in

the chamber will exceed a seating force exerted on the valve member by liquid in the up-stream passage portion without the unit pressure of liquid in the chamber necessarily exceeding that of the liquid in said passage portion; a control passage communicative with said chamber and a place for liquid delivery at low pressure relatively to the pressure in the up-stream passage portion; and a control valve in said control passage, said control valve having ports and passages arranged when in open position to cause diversion of said liquid through the control passage at a rate diminishing the pressure of liquid in the chamber sufficiently that the pressure in the up-stream passage portion prevails in holding the by-pass valve member seated and when in closed position to trap the transferred liquid in said chamber and increase the pressure therein sufficiently to cause said advancement of the plunger structure parts.

2. In apparatus for controlling the flow of liquid through a by-pass passage; a by-pass valve disposed in said passage between up-stream and down-stream portions thereof and including a valve seat circumscribing said passage, and a valve member seatable in a down-stream direction upon said seat for closing such valve; means for unseating said valve member comprising a control cylinder, a plunger structure blocking off a control chamber in the cylinder and comprising axially expanded telescopic parts which are advanceable axially of the cylinder by the force of liquid in said chamber, spring means disposed between said parts and partially compressed thereby, and means precluding further expansion of the telescopic parts by force of the compressed spring while accommodating further contraction of the parts to further compress the spring, the force of said further compressed spring being exerted through one of said plunger parts against the valve member in an up-stream direction to displace the same from said seat pursuant to

advancement of the other of such parts by the force of liquid under pressure in the chamber; a liquid transfer passage communicating between said chamber and the up-stream passage portion, 5 said plunger structure having a transverse area subjected to the liquid in the chamber exceeding the area embraced by the valve seat wherefore an advancing force exerted on the plunger structure by liquid in the chamber will exceed a seating force exerted on the valve member by liquid in the up-stream passage portion without the unit pressure of liquid in the chamber necessarily exceeding that of the liquid in said passage portion; a control passage communicative with said 10 chamber to deliver liquid at a low pressure relatively to the pressure in the up-stream passage portion; and a control valve in said control passage, said control valve having ports and passages arranged when in open position to cause diversion of said liquid through the control passage at a rate diminishing the pressure of liquid in the chamber sufficiently that the pressure in the up-stream passage portion prevails in holding the by-pass valve member seated and when in 15 closed position to trap the transferred liquid in said chamber and increase the pressure therein sufficiently to cause said advancement of the plunger structure parts.
